UNITED STATES PATENT OFFICE.

DANIEL W. CAUSEY, OF NORFOLK, VIRGINIA.

NEEDLE-SHARPENING DEVICE.

1,287,224.

Specification of Letters Patent. Patented Dec. 10, 1918.

Application filed January 26, 1918. Serial No. 213,877.

To all whom it may concern:

Be it known that I, DANIEL W. CAUSEY, a citizen of the United States, residing at Norfolk, in the county of Norfolk and State 5 of Virginia, have invented certain new and useful Improvements in Needle-Sharpening Devices, of which the following is a specification.

This invention relates to a machine for 10 sharpening or repointing needles particularly those adapted for use on talking machines.

It is well known that the usual steel phonograph needle becomes worn when used in 15 playing a single record to such an extent that its further use is undesirable as well as injurious to the record. And, owing to the fact that the greater part of the needle is available for further use, it is desirable to 20 the end of conserving needle steel to repoint these needles, but in so doing it is necessary to provide a point which will not be too sharp and thus cut into the record material and destroy the sound groove. That is to 25 say, phonograph needles must have a perfectly formed point, which point, while apparently very sharp to appearance and touch is in reality more or less blunt, as will appear from a microscopic examination of a 30 perfect needle point. Accordingly, the present invention has primarily in view a device which will initially repoint the needle to a very fine and sharp point to thereby remove any burs, fins, or deflected portions 35 caused by its previous use, and then to subject the same to a polishing operation which smoothes the entire surrounding surfaces of the point and renders the same somewhat round or blunt. Thus, the repointed needle 40 will be provided with a new and perfect point equal in all respects to that originally obtained in the rather tedious and prolonged processes involved in preparing phonograph needles in bulk for the market.

45 Therefore, the present invention has primarily in view a simple, practical and reliable machine which will properly perform the initial sharpening operation and then carry out the necessary steps of polishing 50 and rounding off of the point automatically.

In this latter connection it must be understood that the polishing step does not involve the undoing of what is accomplished by the sharpening in the sense that it puts

an absolutely blunt point on the needle, because as a matter of fact, even after the needle point is subjected to the polishing operation it is still sharp to the touch, and its relatively dull or blunt characteristic can only be appreciated with the aid of a microscope. This dulling or rounding off however, is absolutely essential to the perfect performance and efficiency of a phonograph needle, whereas in the case of sewing machine needles and the like, the simple sharpening of the point alone is sufficient.

A further object of the invention is to provide a device embodying few and simple parts, and which is of such a character that it is particularly adapted for home use, and requires no special skill or manipulation to obtain uniformly satisfactory results.

With the above and other objects in view which will more readily appear as the nature of the invention is better understood, the same consists in the novel construction, combination and arrangement of parts herein-after more fully described, illustrated and claimed.

A preferred and practical embodiment of the invention is shown in the accompanying drawings, in which:—

Figure 1 is a perspective view of my improved needle sharpening machine showing very clearly the combined sharpening and polishing surfaces.

Fig. 2 is a vertical sectional view thereof.

Fig. 3 is a top plan view thereof.

Fig. 4 is a more or less diagrammatic view showing the sharpening and polishing disk in section, and illustrating by the arrow the straight path of movement of the needle across the sharpening portion of the disk while the distorted needle point is being turned down.

Fig. 5 is a view similar to Fig. 4 showing the position of the needle carrier in full lines when the needle has reached the polishing center of the disk and how the same is rocked onto its point by the wheel of the needle carrier engaging with the cam ring; and also showing in dotted lines the position of the needle carrier and needle at the other limit of the rocking movement of the carrier.

Fig. 6 is a detail perspective view of the sharpening and polishing disk showing how the cam surface may be made integral with

the disk instead of in the form of a separate element.

Fig. 7 is a greatly enlarged detail elevation of a needle after it has been repointed 5 by being drawn across the sharpening surface.

Fig. 8 is a view similar to Fig. 7 showing how the point of the needle is rounded off by the polishing step.

10 Similar reference characters designate corresponding parts throughout the several figures of the drawings.

In carrying the present invention into effect, it is proposed to utilize certain fundamental characteristics and features of the

15 machine set forth in my former Patent No. 1,256,978, dated February 19, 1918, and therefore as will be observed from the accompanying drawings, the reference char-

acter 1 designates a supporting base, which in the present instance is preferably made of stamped metal and provided with the flanged skirt portion 2 that forms a housing for a suitable tensioning device for the

25 needle carrier as will hereinafter more fully appear. On the said base 1 is mounted a suitable standard or support 3 having journaled therein a shaft 4 carrying a relatively large driving gear 5 fitted with an operating handle 6, and meshing with a relatively small pinion 7 carried by the shaft 8 having at one end thereof the combined polishing and sharpening disk 9.

This polishing and sharpening disk 35 constitutes one of the chief and most important elements of the present device, since it not only performs the function of initially sharpening the needle, but at the same time provides for polishing and rounding off the

40 needle point to the necessary degree all in the same operation. As will be observed from Fig. 1 this disk is provided with a

polishing surface 10 of any suitable abrasive material such as emery, carborundum or the like while the central portion thereof has secured thereto a dished or counter-sunk polishing member 11, preferably metal. It will of course be understood that this polishing member 11 may be of any other material

45 found desirable and expedient in practice, so long as it adheres to the function of being capable of polishing the needle point to the required extent. In other words under all circumstances the quality of this polishing

50 surface, is finer than that of the sharpening surface which entirely surrounds the same. And, furthermore, as will be observed from Figs. 2 to 5 inclusive, this polishing member 11 is of special formation. That is to say,

55 it is preferably of relatively flat cross section at its center while its outer edge portions are curved upwardly to meet the plane of the sharpening surface 10.

Also, in connection with the disk 10 it is 60 to be noted that the same is provided at its

periphery with a suitable cam ring 12 which is pivoted at diametrically opposite points 13 to the disk so that it may be shifted on these pivots 13 as shown in Figs. 2, 3 and 5. While this way of forming the cam ring has 70 been found practical it will also be understood that the same may be formed integral with the disk 9 as suggested at 12^a in Fig. 6 of the drawings. In both instances the function of the cam ring will be the same, 75 namely, to cause a rocking or swinging of the needle carrier in an arc whose center is the point of the sharpened needle as will presently appear.

At one side of the disk 9, which preferably lies in a vertical plane as shown in the drawings, there is mounted a needle carrier 14 which includes a rotary needle chuck 15 at one end for gripping the needle while the opposite end is provided with a traction 80 wheel 16 for engaging with the abrasive sharpening surface 10 of the disk 9 in the same manner as in my other application previously referred to, whereby the rotation of the disk 9 will cause the entire carrier to 85 be shifted across the face thereof. As shown in Fig. 1 of the drawings, this needle carrier 14 is of substantially T-shaped formation, the shank 17 thereof being hollow and adapted to engage with a spindle 18 90 pivotally connected at its lower end as at 19 with the body portion 20 of a tension device designated generally as T. Thus, the entire needle carrier 14 is detachably engaged with the tension device, and is capable of a 95 swinging movement on the pivot 19 to permit of the shifting of the needle from the periphery of the disk toward the center thereof as shown in dotted lines in Fig. 1, and as also fully set forth and explained in 100 my former application.

The purpose of the tension device T is to hold the needle carrier 14 yieldably against the surface of the disk 9, whereby when the latter rotates there will be sufficient friction between the wheel 16 and surface 10 to produce the necessary tractive effect. The greater the tension on the needle carrier, the faster it will travel across the face of the disk while on the other hand when the 115 tension is lessened the shifting of the needle carrier will be more rapid.

As will be observed from the drawing, the body portion 20 of the tension device T which has pivoted thereto the spindle or arm 18 at 19, has also pivotally attached to its opposite corner as at 21 a suitable fiber needle holder 22 which may be swung over into such a position that fiber needles clamped therein may be sharpened on the 125 surface 10. When sharpening these needles the needle carrier 14 may be removed since the hollow shank 17 detachably engages the arm or spindle 18. And, as may also be observed, the said body portion 20 is piv- 130

totally supported in suitable eyes 23 which may be struck up from the metal of the base 1 or otherwise conveniently formed, while the lower portion of the body may be slit in such a manner that one leg thereof may be bent up into a plane at right-angles to the body to form a thumb piece 24 to assist in pulling the entire tension device and needle carrier away from the face of the disk on its 10 pivots in the eyes 23, while the other leg 25 may be left in the plane of the body and project through a slot 26 in the base 1 to be engaged by one end of the tension spring 27, whose opposite end has a swivel connection with a tension adjusting screw 28. The head 29 of the latter is conveniently exposed in a readily accessible position whereby the operator may rotate the same one way or the other to place the 20 spring 27 under more or less tension, and consequently cause the wheel 16 of the needle to have a greater or less tractive engagement with the face of the disk 9.

Referring now to the manner of operation of the present device it may be noted that the cam ring 12 is first deflected from the plane of the disk 9, and then the needle carrier 14 with the needle N in the chuck 11 is placed at the peripheral edge of the 30 sharpening surface 10 while the wheel 16 of the carrier engages with the portion of the surfaces 10 of smallest diameter. Then, the disk 9 is rotated by manipulating the gears 5 and 7 through the handle 6, and the 35 needle N will be rotated and shifted from the peripheral edge of the disk toward the center, or in other words, the needle will be drawn across the sharpening surface 10 toward the polishing surface 11, and at the 40 same instant the point of the needle N passes from the surface 10 into the dished polishing member 11, the wheel 16 leaves the periphery of the disk 9 and travels on the cam ring 12. Obviously, the continued 45 rotation of the disk 9 with the wheel 16 on the cam ring 12 will cause the rocking of the needle carrier, with the extreme limit of rocking movement taking place at the wheel end of the carrier as shown in Fig. 5, 50 and at the same time having the effect of rocking the needle N from heel to toe on the curved side wall of the polishing member 11 whereby the needle point will be 55 polished and at the same time made somewhat round or blunt as suggested in the greatly magnified illustrations of the needle in Figs. 7 and 8. Thus, it will be apparent that the continued rotation of the disk 9 with the needle N in the position 60 shown in Fig. 5 will polish the point and take off the extremely sharp extremity which results from the sharpening operation. With the construction shown in the present drawings it will of course be apparent that the wheel end of the carrier 14

will oscillate to both sides of the plane of the sharpening surface 10 of the disk 9, and in so doing the full length of the needle point will be uniformly polished from the heel to the toe, or in other words from the 70 point where the needle begins to taper to its operative extremity.

Furthermore, it may be noted that in addition to the important aspect of the present invention which provides a combined sharpening and polishing surface it is proposed to so construct the disk having these special features and characteristics so that it will automatically effect an oscillating or rocking of the needle carrier. The rotation of the 80 disk causes the entire carrier to be shifted across the face thereof as long as the wheel of the carrier remains in engagement with the flat surface of the disk, but when the wheel leaves this flat surface and rides upon 85 the cam element of the disk, there is a new movement imparted to the needle carrier which takes place in a plane at substantially right angles to the movement which takes place when the carrier is shifted across the 90 face of the disk. That is to say, the simple rotation of the disk 9 first causes the needle carrier to have a movement in a plane parallel to the surface of the disk while on the other hand when the wheel of the carrier engages the cam surface it has an oscillating 95 movement in a plane at right angles to the surface of the disk. These two separate and distinct movements occurring in substantially one and the same operation, combines 100 with the novel sharpening and polishing surfaces of the disk, to quickly and accurately produce the desired point on the needle.

Without further description it is thought 105 that the many features and advantages of the present invention will be readily apparent, and it will of course be understood that changes in the form, proportion and minor 110 details of construction may be resorted to without departing from the spirit of the invention or scope of the appended claims.

I claim:

1. A needle sharpening machine including 115 a rotary member carrying an abrasive surface and a polishing surface, and a shiftable needle carrier operatively related to both of said surfaces.

2. A needle sharpening machine including 120 a rotary member carrying an abrasive surface and a polishing surface, a needle carrier, and means for feeding the needle carrier across the abrasive surface into operative relation to the polishing surface.

3. A needle sharpening machine including 125 a rotary member carrying an abrasive surface and a polishing surface, a needle carrier, means for feeding the needle carrier across the abrasive surface into operative relation to the polishing surface, and means 130

for imparting a rocking movement to the needle carrier when cooperating with the polishing surface.

4. A needle sharpening machine including a rotary member carrying an abrasive surface and a polishing surface located within the central part of the abrasive surface, and a shiftable needle carrier operatively related to both the said surfaces.
5. A needle sharpening machine including an abrasive disk, a needle carrier for holding a needle at an angle to the disk, and means for oscillating the end of the needle carrier opposite the needle in a plane at right angles to the surface of the disk.
6. A needle sharpening machine including a disk having a sharpening surface, and a central metal polishing cup including a relatively flat bottom and a curved side wall, a needle carrier for holding a needle at an angle to the disk, and means for oscillating the end of the needle carrier opposite the needle in a plane at right angles to the surface of the disk, whereby the needle may be rocked on its point to coöperate with said curved wall of the cup.
7. A needle sharpening machine including a disk having sharpening and polishing surfaces, a needle carrier including a wheel for contacting with said disk and adapted to be shifted across the face thereof when said disk is rotated, and means carried by said disk for oscillating the wheel end of the carrier.
8. A needle sharpening machine including a combined sharpening and polishing disk, a needle carrier having a frictional engagement with the sharpening surface of the disk and adapted to be shifted in a plane parallel to the surface of the disk upon the rotation thereof, and means carried by the disk for imparting an oscillating movement to one end of said carrier.
9. A needle sharpening machine including a combined sharpening and polishing disk having a flat sharpening surface and a dished central polishing surface, a rotatable needle carrier having frictional engagement with the disk and adapted to be shifted across the face thereof as it rotates, and means for rocking the needle carrier.
10. A needle sharpening machine including a combined sharpening and polishing disk, a rotary needle carrier adapted to receive a needle in one end and having a traction wheel at the other, means for causing said wheel and needle of the carrier to engage with the sharpening surface of the disk whereby when the needle is located at the periphery of the sharpening surface the wheel will engage with the smallest diameter thereof and upon rotation of the disk the needle will be shifted toward the center and the wheel toward the periphery, a cam ring located at the periphery of the disk and

adapted to receive the wheel of the carrier as it leaves the periphery of the sharpening disk to oscillate the entire carrier, with the point of the needle which contracts with the polishing surface of the disk acting as the center of the arc of oscillation.

11. A needle sharpening machine including a rotary disk, having sharpening and polishing surfaces, a needle carrier having means at one end for clampingly engaging the needle and a wheel at the other end for engaging with the surface of the disk and maintaining the needle at a fixed angle to the disk, and cam means carried by the disk for engaging with the wheel of the carrier as the same is shifted toward the periphery of the disk, said cam means serving to rock the carrier to increase the angle at which the needle engages with the disk.

12. A needle sharpening machine including a rotary disk having a sharpening surface and a polishing surface, a needle carrier having means at one end for holding a needle and a wheel at the other end for engaging with the sharpening surface of the disk, and a cam element located at the peripheral edge of the disk for engaging with the wheel after it leaves the flat surface of the disk to impart an oscillating movement to the carrier.

13. A needle sharpening machine including a rotary disk having a sharpening surface and a polishing surface, a needle carrier having means at one end for holding a needle and a wheel at the other end for engaging with the sharpening surface of the disk, and a cam ring carried by the peripheral edge of the disk and adapted to engage with the wheel of the carrier after the same leaves the flat surface of the disk to rock the needle in the other end of the carrier from the heel to toe.

14. A needle sharpening machine including a combined sharpening and polishing disk, a needle carrier having a traction feeding engagement with said disk, and a tension device for said needle carrier including a pivotally supported member and means for adjusting the tension of said member.

15. A needle sharpening machine including a base, a combined sharpening and polishing disk rotatably supported on the disk, a needle carrier engaging with said disk, a tension device having said needle carrier pivotally connected therewith and including a body member pivotally supported on said base, a spring for engaging with a portion of said body member on the opposite side of the pivot to that which the needle carrier is connected, and a manually adjustable screw engaging the other end of said spring.

16. A needle sharpening machine including a flanged metallic base, a combined sharpening and polishing disk rotatably supported thereon, a needle carrier for en-

gaging with said disk, a tension device pivotally connected with said needle carrier and including a body portion and pivotally supported in said base and also having a portion 5 projecting through a slot in said base, a spring engaging the portion of said body which projects through said slot and housed within said flanged base, and a thumb screw mounted in the flange of said base and hav-

ing a swivel connection with the end of said 10 spring opposite that engaging with the depending portion of said body.

In testimony whereof I hereunto affix my signature in the presence of two witnesses.

DANIEL W. CAUSEY.
